CLAIM

The ornamental design for a camisole, as shown and described in the Figures.

DESCRIPTION

FIG. 1 is a front perspective view of a camisole, showing my new design;

FIG. 2 is a rear perspective view thereof;

FIG. 3 is front elevational view thereof; shown in a flattened condition; and,

FIG. 4 is a rear elevational view thereof.

The features shown in broken lines in FIGS. 1 and 2 are for illustrative purposes only, and form no part of the claimed design.
